UNITED STATES PATENT OFFICE.

JOHN J. BACH, OF PHILADELPHIA, PENNSYLVANIA.

CIGAR-BUNCHING MACHINE.

SPECIFICATION forming part of Letters Patent No. 390,940, dated October 9, 1888.

Application filed April 12, 1888. Serial No. 270,382. (No model.)

To all whom it may concern:

Be it known that I, JOHN J. BACH, a citizen of the United States, and a resident of Philadelphia, Pennsylvania, have invented 5 certain Improvements in Cigar-Bunching Machines, of which the following is a specification.

One object of my invention is to construct a cheap and simple form of cigar-bunching machine; and a further object is to provide for 10 making bunches of different shapes and sizes. These objects I attain in the manner herein-after set forth, reference being had to the accompanying drawings, in which—

15 Figure 1 is a longitudinal section of a cigar-bunching machine constructed in accordance with my invention, and Fig. 2 is a plan view of the same.

The base-block A of the machine, which is 20 preferably made of wood, has a segmental upper surface, *a*, in which is formed a recess, *b*, extending transversely across the block and adapted for the reception of the mold B, the opening in which is of the desired shape for 25 the bunch.

To the projecting portions of a rod, *d*, passing transversely through the block, are hung the opposite ends of a yoke, *F*, the segmental upper surface of the block A being concentric, 30 or substantially concentric, with the pivot-pin *d* of the yoke.

To the opposite side bars of the yoke *F* are adapted the journals *g* of a roller, *h*, which is so located in respect to the pivot-bolt *d* that 35 as the yoke is vibrated said roller *h* will be caused to travel in a path concentric with and a short distance from the segmental top of the block A. The block A has a longitudinal projection, *A'*, to the upper face of 40 which is secured the base *i* of a plate, *G*, said base having a slot, *i'*, for the reception of a bolt, *m*, so that the plate *G* can be adjusted longitudinally on the projection *A'*, the securing of the plate in position after adjustment 45 being effected by means of a nut, *m'*, on said bolt *m*.

To a transverse rod, *n*, carried by lugs at the upper end of the plate *G*, is secured one 50 end of an apron, *J*, which passes over the roller *h* of the yoke *F*, and is secured at its

opposite end to the end of the block A. To the same end of the block are secured elastic fingers *p*, which are acted upon by thumbscrews *s*, so that they can be adjusted in respect to the end of the block.

The operation of the machine is as follows: The parts being in the position shown in Fig. 1, the tobacco of which the bunch is to be made is deposited upon the apron *J*, and pressed with the latter into the mold B, the 60 tobacco being so disposed as to conform to the shape of the mold. By means of its handle *t* the yoke *F* is then moved over in the direction of the arrow, Fig. 1, so as to close the apron over the bunch of tobacco in the mold. As the 65 movement of the yoke is continued, the bunch is lifted from the mold and rolled forward in the loop of the apron over the segmental top of the block A, as shown by the dotted lines 1, Fig. 1, until it is finally deposited in the 70 holder formed by the spring-fingers *p* at the end of the block, as shown by the dotted lines 2, Fig. 1. It is usual, however, to wrap a binder around the bunch at the same time that it is formed, and when this is to be done 75 a leaf, *x*, of tobacco, of the proper size for the binder, is laid upon the apron *J* before moving the yoke; and I prefer to back this binder with a strip, *y*, of paper or equivalent material, which is rolled with the binder around 80 the bunch, and aids in retaining the bunch in shape during the subsequent drying operation, so that the binder is relieved from strain and a lighter and cheaper binder can be used than is otherwise required.

Any desired size or shape of mold B may be used in connection with my improved bunch-former, the mold being readily detachable from the recess in the block; and, owing to the adjustability of the plate *G*, the amount 85 of slack in the apron *J* can be increased or diminished, and the machine thus adapted for forming bunches of any desired size.

Having thus described my invention, I claim and desire to secure by Letters Patent—

95 The combination of the block having a segmental top with flat-faced projection adjacent thereto, and a molding-recess in said segmental top, the wrapping-belt, the yoke having a roller for acting on said belt, and the 100

right-angled slotted adjustable plate carrying a roller to which is attached one end of the wrapping-belt, said plate being situated upon the flat-faced projection of the block and 5 being movable thereon from and toward the segmental portion of the block, all substantially as specified.

In testimony whereof I have signed my name to this specification in the presence of two subscribing witnesses.

JOHN J. BACH.
